UNITED STATES PATENT OFFICE

ALFRED HUSTER, OF KIEL, GERMANY, ASSIGNOR TO FRIED. KRUPP GERMANIAWERFT AKTIENGESELLSCHAFT, OF KIEL-GAARDEN, PRUSSIA, GERMANY

WATER TUBE BOILER

Application filed February 26, 1929, Serial No. 342,802, and in Germany March 10, 1928.

The invention relates to water tube boilers and has for its object an improved arrangement of the water tubes which immediately are exposed to the heat radiated by the firebox.

In various types of boilers such as upright water tube boilers and marine boilers it is common to bend the tubes of several rows of water tubes so that all of these tubes will lie in one plane and form a gas tight tube wall. In order to facilitate the bending of these tubes, they are made of a comparatively small diameter. If these tubes are directly exposed to the heat radiated from the firebox, as is the case in modern boilers equipped with pulverized fuel burners, the permissible length of these tubes is materially decreased, due to the fact that their small section of circulation renders them liable to overheating. The invention has for its object to enable the use of these advantageous tube walls formed by uniting several tube rows in one plane, even with great heights of the firebox and correspondingly great length of the tubes. This object is obtained according to the invention by arranging in front of the tube wall, as a protection from the immediate heat radiation, at least one row of tubes which is composed of laterally spaced water tubes having a greater diameter than the tubes of the gas-tight tube wall.

In order to allow of the invention to be more easily understood, an embodiment of same is illustrated by way of example in the accompanying drawings in which

Figure 1 is a sectional view of a water tube boiler, and

Figure 2 is a fragmentary section on line II-II of Figure 1.

Referring to these figures, 1 denotes the upper drum and 2 the lower one of the boiler between which drums extends a nest of water tubes 3 the inner side of which is exposed to the heat radiation of the firebox 4. In front of this nest of tubes 3 is arranged a protective tube wall 5 formed by three tube rows united in one plane and the length of the tubes of which is greater than it would be admissible with regard to their small diameter and due to their being exposed immediately to the

heat radiation. To enable nevertheless this length, two rows of tubes 6 and 7 of greater diameter are arranged in front of the gas-tight tube wall 5 the tubes of which rows are spaced from and staggered with regard to 55 one another.

By the practice of this invention, a gas-tight tube wall can be arranged, formed by uniting in one plane several rows of smooth tubes, of small diameter. This may be done 60 despite the fact that a firebox of great height is desired, resulting in a correspondingly greater length of water tubes, because the wall may effectively be protected from the intense heat radiation from the firebox. 65

I claim:

In a water tube boiler of the class described a water tube wall composed of tubes of normal small diameter, and a plurality of rows of spaced water tubes arranged in staggered relation to one another in front of said tube-wall and consisting of tubes having a greater diameter than those of said tube wall, and arranged to exclude from said wall at least all direct radiation substantially normal 70 to the plane of said wall. 75

The foregoing specification signed at Hamburg, Germany, this 5th day of February, 1929.
